UNITED STATES PATENT OFFICE.

CHARLES WEST AND ARTHUR GREEN, OF LONDON, ENGLAND.

COMBINED DECK CHAIR AND ROCKING-CHAIR.

Application filed June 3, 1922. Serial No. 565,710.

To all whom it may concern:

Be it known that we, CHARLES WEST, of 65 Dunloe Avenue, London, N. 15, England, and ARTHUR GREEN, of 271 Camden Road, 5 London, N. 17, England, both subjects of the King of Great Britain and Ireland, have invented certain new and useful Improvements in or Relating to Combined Deck Chairs and Rocking-Chairs, of which the 10 following is a specification.

This invention relates to an improved construction of combined deck chair and rocking chair and refers more particularly to chairs of the kind consisting of substantially rectangular back and seat frames connected together on opposite sides by a pair of pivotal links, rods or bars, so as to permit the same to rock, the canvas or other material forming the seating being 15 suspended from the top of the back frame and the front frame of the seat frame.

The object of the present invention consists in an improved construction of chairs of this kind which will be simple and inexpensive to construct, more comfortable in use and in which the relative positions of the frames may be adjusted by the occupant of the chair without rising therefrom. A further feature of the invention consists in 20 an improved construction and arrangement of the links and frames which permit the chair to be folded to a substantially flat condition, the links or rods co-operating with stops to ensure the chair being opened 25 out in the correct manner. Another object is to provide extension of the lower ends of the feet members of the seat frame to form stops to limit the movement and to also provide means for locking the frame in 30 any adjusted position.

According to the invention, we provide two substantially rectangular frames, one of which constitutes the back frame and the other the seat frame. The canvas or the like 45 seating is attached to the front cross member of the seat member of the seat frame and to the upper cross member of the back frame. The sides of the back frame are preferably straight and are pivotally connected at the lower ends of the bars, rods 50 or links, located on each side.

The lower end of the seat frame is also pivotally connected to the side bars at or near their ends.

55 The side members of the seat frame are

slightly bent or curved in opposite directions at their ends, the upper forward ends are bent or inclined forwardly and downwardly, whilst the rear ends are bent or inclined rearwardly and upwardly. By this means 60 the cross member at the upper forward end may be located at a lower level than is possible with frames having straight side members. The rear ends of the curved side members of the seat frame are pivotally connected to the side bars or the like on each side at a point a short distance from their ends so as to provide an extension which acts as a stop to limit the extent of rocking 65 of the frames relatively to one another. 70

In order to facilitate folding of the chair into a substantially flat condition, we prefer to connect the back and seat frames to the lower side bars or the like by horizontal pivots or pins passing therethrough, the 75 side members of the back frame being located on the inside of said bars and the curved side members of the seat frame on the outside thereof. By this arrangement, the extension of the curved sides of the seat 80 frame contact with the ground or other surface on which the chair rests to limit the rocking motion thereof.

The side bars or the like rest entirely upon the ground or other surface whilst the ends 85 of the seat and back frame are supported above the ground.

In this construction, the lower end of the back frame is pivotally connected at its ends to the side bars at or near their 90 forward ends, whilst the rear ends of said side bars are connected together by a cross member, which raises the rear ends off the ground and permits limited rocking of the seat frame about its pivotal connection without the extension thereof contacting with 95 the ground.

Various means may be adopted for securing the frames in any desired position so as to enable the occupant to adjust the chair 100 to afford the maximum comfort without rising.

In order that the invention may be readily understood, reference is made to the accompanying drawings, in which:—

Fig. 1 is a side view of the deck chair.

Fig. 2 is a perspective view of the seat portion and part of the back portion.

Fig. 3 is a side view of the chair showing the same folded up.

105

110

Fig. 4 is a perspective view to a larger scale showing the securing means for the chain between the back and seat frames.

Fig. 5 is a similar view showing one method by means of which the chain may be employed for securing the frames of the chair together in the folded condition.

Fig. 6 shows a modified construction of the means for securing the frames in any 10 adjusted position.

Figs. 7 and 8 show two constructions in which resilient means are employed to secure the two frames of the chair against rocking.

Referring to the construction shown in Figs. 1-4, the chair is built up of two substantially rectangular frames hereinafter referred to as the seat frame and the back frame, respectively. The seat frame comprises longitudinal side members 10, 11 connected at their upper forward ends by a cross member 12. The back frame consists of longitudinal side members 13, 14 respectively connected at their upper ends by a 25 cross member 15 and in the neighbourhood of their lower ends by a cross member 16. As is usual with deck chairs, the back frame is made somewhat longer than the seat frame, as shown in the drawings, whilst the 30 width of the seat frame is preferably slightly greater than the width of the back frame or vice versa in order to allow movement of one within the other. The lower end of the back frame is connected to the 35 lower end of the seat frame on each side by the bar, rod or the like 17, one end of which is pivoted to the seat frame at a point 18, whilst the opposite end is similarly connected to the back frame at a point 19. The 40 frames are also connected by a second bar, rod, or the like 20 one end of which is pivoted to the back frame at a point 21, approximately mid-way between its ends whilst the opposite end of said bar is 45 connected to the seat frame 22 a short distance from the upper forward end of the frame.

The canvas or like seating 23 is supported or attached to the cross member 15 of the back frame and at the opposite end to the 50 cross member 12 of the seat frame.

The lower ends of the side members 13, 14 of the back frame are pivotally connected at their extreme ends to the bars 17 at a 55 point 19, a short distance from the ends thereof, whilst the lower curved ends of the side members 10, 11 of the seat frame are similarly connected at a point 18, to the rear ends of the bars 17, the arrangement being such that the ends of both the bars 17 and the side members 10, 11 extend slightly beyond the point 18.

The front and rear ends of the two bars 17 rest upon the ground, the rear ends being 60 connected by a cross member 24, the projecting lower surface of which, when rest-

ing upon the ground raises the rear ends of the bars 17 slightly as shown in Fig. 1.

It will thus be seen that the whole chair rests on the rods 17, and the cross member 24. The object of this arrangement is to 70 prevent any movement between the frames and the ground when the chair is rocked, as in some cases, for instance, if the chair is resting upon soft ground or sand the rocking movement of the lower ends of the 75 frames resting on the ground is likely to cause holes which after a time are likely to become enlarged and thus have a tendency to cause the chair to become embedded in the ground. By this arrangement of the 80 bars 17, and the cross members 24, in the manner described, this disadvantage is overcome and, further, the bars 17 and the cross member 24 offer a greater resistance to the 85 ground than with the ordinary deck chairs as at present constructed owing to their having a considerably larger area of support.

The extensions 10^a, 11^a of the side members 10, 11 at their rear ends are arranged to prevent 90 rocking beyond certain limits and the point of connection 18 of said members being slightly raised from the ground, the chair may be rocked rearwardly within reasonable limits as shown by dotted lines in 95 Fig. 1, the extensions 10^a, and 11^a acting as a safeguard, especially when the chair is resting on sloping ground.

The side members 10, 11 of the frame are 100 slightly bent or curved in opposite directions at each end, the curvature at the upper forward end enabling the front cross member 12 to be located at a lower level than is possible with frames having straight side 105 members.

The arrangement of the connecting bars 17 and 20 between the vertical side members 10, 11, 13 and 14 of the back and seat frames respectively also facilitates the folding of 110 the chair into a substantially flat condition as shown in Fig. 3.

Various means may be adopted for securing the frames in any desired position, so as to enable the occupant to adjust the chair to afford the maximum comfort without 115 rising.

In order to enable the chair to be secured against rocking, if the user so requires, we provide a chain, cable, cord or the like or a plurality of such devices, by 120 means of which the frames are held together relatively to one another. Where a chain is employed, one end thereof may be attached to the lower cross member 16, of the back frame whilst at its opposite end one 125 of its links is engaged over a hook, pin or the like secured to the cross member 12 of the seat frame as shown in Figs. 1 to 3.

The cross member 12 of the seat frame has 130 secured to its under face, preferably in the

centre, a U shaped bracket 25 through which the chain 26 can freely move. The outer side 27 of the bracket is cut away to form a tongue or projection 28 which is bent 5 slightly inwardly, as shown in Fig. 3, whilst the lower opposite edge may be formed with a guide or the like 29 bent outwardly to facilitate the movement of the chain. The tongue or projection 28 is of such a size that 10 when the links of the chain are passed over its ends they both tend to fall by their own weight into engagement with the tongue thus securing the chain in any desired position. By this means the occupant of the 15 chair is able to adjust the frames to any desired position without rising from the chair, as by holding the chair in an upward direction the links pass over the inwardly projecting tongue 28 and when the frames have 20 been moved to the desired position the link for the time being above the end of the tongue engages therewith and locks the frames together.

When the chair is folded up as shown in 25 Fig. 3, this chain may serve for retaining the ends of the frames in their collapsed condition, the looped portion of the canvas seating 23 being wound round the adjacent members 12 and 15 to which its ends are 30 connected, whilst the chain 26 is wound round the outer side of the canvas, the chain being provided with a hook or knob 30, which engages one of the links of the chain as shown diagrammatically in Fig. 5, and 35 thus secure the two frame members in the folded or collapsed position.

The frame members may be locked in any 40 adjusted position by the means illustrated in Fig. 6, in which the rod 20 connecting the upper end of the seat frame to the back frame has pivotally mounted thereon a bar or rod 31, provided with a series of notches 32 on one side and with a somewhat deeper notch 33 on the opposite side. This bar is 45 pivoted to the bar 20 at the point which normally is disposed slightly in front of a pin or stud 34 fixed to the side member 14 of the back frame. When the chair is rocked any of the notches 32 may be engaged with the pin 34 according to the position of adjustment required. When it is 50 desired to adjust the chair to a position in which the back frame is inclined to its maximum extent, the bar 31 is rotated about its pivot so as to bring the notch 33 on the opposite side of the bar into engagement 55 with the stud 34. The object of this arrangement is to enable the bar 31 to engage the pin 34, when the pivotal point from 60 which the bar is supported is moved to the opposite side of the vertical line passing through the stud 34.

In some cases it may be found desirable 65 in order that the chair may not be subjected to sudden strains or stresses to provide re-

sistant means for connecting the frames together.

Two methods of connecting the frames together with this object in view are shown in Figs. 7 and 8.

In the construction shown in Fig. 7, the lower end of the chain 35 is connected to one end of a coil spring 36, the opposite end of which is connected to the cross member 16 connecting the side members 13, 14 of the 70 back frame. With this construction the chain may be operated to engage the tongue of the U shaped bracket 25 as in the construction described with reference to Figs. 1 and 4, the spring serving to take up any 75 shocks or strains caused by a person violently sitting in a chair and adding considerably to the comfort of the user.

In the construction shown at Fig. 8, the lower end of the chain 35 is connected to a 80 rod 39, passing through a hole or slot in the transverse member 16, connecting the side members 13 and 14. Between the head 40 of this rod and the cross member 16 is a 85 coil spring 41.

By this means any violent strain on the chain 35 is taken up by the spring 40.

If desired the chain may be entirely eliminated, the spring being connected at one 90 end to the cross bar 16, and at the other end to the cross member 12 of the seat frame.

The cross member 16 may if desired be 95 rotatable, so that the rod and spring do not prevent folding up of the chair.

In order to ensure the frames being opened 100 out from their collapsed or folded position, in the proper manner, a suitable stop may be provided on one of the frames against which a portion of the other frame abuts when the frames are folded together. One 105 simple method of effecting this object is shown by way of example in Fig. 1, in which one or both of the side members 13, 14 of the back frame are provided in the neighbourhood of their upper ends with a 110 projecting member 37 arranged in such a manner as to engage the end of the connecting bar or rod 20 as shown in dotted lines at Figs. 1 and 3, the end of the bar or bars 20 being preferably cut off at an angle 115 as shown at 38. By this means the opening of the frames otherwise than in the correct manner will be prevented by the stops 37. It will of course be understood that the 120 stops may be located in any other position if desired.

It will be understood that the details of construction may be modified without departing from the principle of the invention.

What we claim as our invention and desire to secure by Letters Patent in United States is:—

1. A combined deck chair and rocking chair comprising in combination substantially rectangular back and seat frameworks, 130

- 1 a base framework on which the chair rests, comprising side members and a transverse member on the underside and at the rear thereof, the side members of the seat framework being pivoted at their lower ends to the side members of the base framework at the rear, the side members of the seat framework being extended beyond the pivots to form limiting stops, the side members of the back framework being pivoted at their lower ends to the side members of the base framework at the front, a seating fabric having its lower front portion supported by a member between the upper ends of the sides of the seat framework and its upper portion supported by a member between the upper ends of the sides of the back framework, link members on each side connecting the side members of the seat and back frames, and means for maintaining the said frames in any adjusted position, for the purposes set forth.
2. A combined deck chair and rocking chair comprising in combination substantially rectangular back and seat frameworks, a base framework on which the chair
- 5 rests, comprising side members and a transverse member on the under side and at the rear thereof, the side members of the seat framework being pivoted at their lower ends to the side members of the base framework at the rear, the said side members of the seat framework being extended beyond the pivots to form limiting stops, the side members of the back framework being pivoted at their lower ends to the side members of the base framework at the front, a seating fabric having its lower front portion supported by a member between the upper ends of the sides of the seat framework, and its upper portion supported by a member between the upper ends of the sides of the back framework, link members on each side connecting the side members of the seat and back frames, and a chain adjustable between members of the back and seat frames for maintaining the said frames in any desired position.
- 10 In testimony whereof we have hereunto subscribed our names.
